UNITED STATES PATENT OFFICE.

ALONZO B. CROSS, OF MOBILE, ALABAMA.

PIANO-ACTION JOINT.

1,176,655.

Specification of Letters Patent. Patented Mar. 21, 1916.

Application filed July 18, 1914. Serial No. 851,802.

To all whom it may concern:

Be it known that I, ALONZO B. CROSS, a citizen of the United States, residing at Mobile, in the county of Mobile and State 5 of Alabama, have invented a new and useful Piano-Action Joint, of which the following is a specification.

This invention relates to piano actions, its principal object being to eliminate practically all of the disadvantages incident to the use of piano actions such as commonly employed. For example, flanges on which the movable parts of the action have been mounted, have heretofore been provided necessarily. These flanges contain pin holes which are bushed or lined with cloth. The different parts work upon pins which are secured firmly in position and work loosely in the holes in the lined flanges. It is a well known fact, however, that changes of temperature and atmospheric conditions cause the flanges to expand and contract. In damp weather the entire action often becomes sluggish so that repetition is seriously interfered with and the parts often stick to such an extent that they will not work. Furthermore, piano actions as ordinarily constructed, are provided with several springs all of which become weak after long use and often break. This is especially true of the damper spring. The jack spring commonly used is made of coiled wire and soon becomes weakened to such an extent that it interferes with proper repetition and often fails to work.

It has been found that the bushings or linings used in connection with the flanges very quickly wear out, especially when the action is subjected to constant use, this leaving the action loose and noisy. Furthermore the flange pins often corrode under the action of the moisture contained in the atmosphere, thereby causing the action to work poorly.

As before stated, one object of the present invention is to overcome the objectionable features mentioned by providing connections between the parts in the form of flat springs of steel or other suitable metal, these springs serving not only as hinges but also constituting means to hold the parts normally in predetermined positions rela-

tive to each other and to prevent the parts from moving out of line.

Another object is to provide simple means whereby the spring strips can be quickly and securely attached to the parts, it being possible to readily remove the springs without completely detaching the holding means provided therefor.

A further object is to provide a structure which dispenses with the usual hammer spring rail, the hammer butt spring, the jack springs and some other parts heretofore used in piano actions, and the flanges which have heretofore been used upon the whippen, jack, hammer butt, abstract lever and damper lever.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a side elevation of a piano action embodying the present improvements, the parts being shown in their normal positions, the action rails being in section. Fig. 2 is a similar view showing the relative position of the parts immediately subsequent to striking the strings with the hammer and before the key has been released. Fig. 3 is a front elevation of the structure shown in Fig. 1. Fig. 4 is a perspective view of one of the spring connections. Fig. 5 is a detail view of a holding plate to be used with a spring connection. Fig. 6 is a perspective view of another form of connecting spring.

Referring to the figures by characters of reference 1 designates the usual key having an adjustable capstan screw extending under and adapted to bear upwardly against 100 the abstract 3. This abstract has a link 4 pivotally connected to it and said link is in turn connected to an action rail 5 by means of a spring connection 6. This connection is

made up of a thin strip of spring metal, preferably hardened steel, said strip being extended at one end under the action rail 5 and at its other end on top of the link 4. A 5 clamping plate 7 is mounted upon each end portion of the strip 6, one of the plates being attached to the action rail 5 by means of suitable screws 8, while the other plate, is similarly secured to the link 4. As shown 10 in Fig. 6, each end portion of the strip 6 has a screw receiving notch 9 therein while apertures 10 are provided for the other screws extending through the plates 7. Thus the connecting strip 6 can be securely 15 held against movement relative to the rail 5 and link 4 and not only serves as a hinged connection between the link and the rail but also as a spring for holding the link normally in a predetermined position relative 20 to the rail. The strip 6 is of the same width as the link 4 and will prevent the link from swaying laterally or shifting out of line.

The upper end of the abstract 3 is pivotally connected as ordinarily to a wippen 11. 25 This wippen extends under an action rail 12 and is preferably formed in its upper face with a recess 13 designed to embrace the lower edge of the action rail 12 during the pivotal movement of the wippen. Said wippen is connected to the bottom of the action rail 12 by a strip 14 preferably formed of hardened steel, this strip being similar to the strip 6 hereinbefore described and being attached to the rail 12 and wippen 11 in the 30 same manner. Thus strip 14 not only constitutes a hinged connection between the rail 12 and the wippen 11 but also serves as a spring for holding the wippen normally in a predetermined position relative to the action rail and to prevent said wippen from swinging laterally out of line. A damper spoon or tongue 15 extends from the back end of the wippen and in front of the lower end of the damper lever 16, which lever is 35 connected to the upper portion of the front face of the rail 12 by means of a connecting strip 17. This connecting strip is preferably made of hardened spring steel, the end portions of the strip being connected to the 40 damper lever and to the rail 12 in the same manner as are the strips 6 and 14. This connecting strip 17 is preferably formed with an intermediate bend so that under normal conditions the damper lever will be 45 held at such an angle as to hold the damper head 18 in contact with the string S.

The front end of the wippen 11 extends under a regulating rail 19 carrying a regulating screw 20 to the lower end of which 50 is secured a regulating button 21. This button is disposed above and in the path of the foot 22 of a jack 23, the heel portion of the jack being mounted to rock upon the top of the wippen. This jack is connected

to the wippen by a spring strip 24 preferably formed of hardened spring steel and which strip is secured to the jack in the same manner as the strips 6, 14 and 17. The lower end portion of the spring strip 24, however, is extended into a slot 25 formed in 65 the upper portion of the wippen, this inserted portion of the spring being held in place by a wedge 26 which is driven into the slot, the several parts being then glued together in any suitable manner. This 70 spring strip 24 serves not only as a hinged connection between the jack and the wippen but also serves as a spring for holding the jack normally at a predetermined angle to the wippen and to prevent the jack from 75 twisting or tilting laterally out of line with the wippen.

The hammer butt 27 is connected to the action rail 12 by a spring strip 28 similar to the strip 17 heretofore described, this 80 strip being secured to the action rail 12 and to the hammer butt 27 in the same manner as the strip 17 is fastened. The hammer butt is arranged in front of a hammer rail 29 as ordinarily, the hammer 30 being so 85 positioned as to strike the string S when the action is set in motion. A back stop 31 is connected to the hammer butt 27 and the jack 23 projects between this back stop and the toe 32 of the hammer butt.

Importance is attached to the fact that by using clamping plates such as shown in Fig. 5, it is possible, simply by removing the screws entering the openings 10 in the various spring strips, to withdraw these spring 100 strips from engagement with the other screws extending through the strips or plates 7. Consequently while a hammer, wippen or other part is being removed the clamping strip or plate 7 will be retained in 105 position thereon while the spring strip remains attached to its rail and slips from engagement with the part being removed. To replace a hammer, wippen, or the like, it is merely necessary to slip the part back on the 110 string, replace the screw in hole 10 and tighten the screw that fits in recess 9.

By setting the lifter spring at different angles, the touch can be made light or heavy as desired.

What is claimed is:—

1. A piano action including separate parts, one of which is movable relative to the other, a flat spring strip, separate connecting means extending through the strip and 120 into the respective parts, and means engaging the ends of the strip and the respective parts for holding said parts against pivotal movement relative to the strip.

2. A piano action including separate 125 parts, one of which is movable relative to the other, a flat spring strip, separate connecting means extending through the strip and

into the respective parts, means engaging the ends of the strip and the respective parts for holding said parts against pivotal movement relative to the strip, and clamping 5 plates engaging those portions of the strip lapping the parts of the action, said plates being engaged by the connecting means.

In testimony that I claim the foregoing as my own, I have hereto affixed my signature in the presence of two witnesses.

ALONZO B. CROSS.
